UNITED STATES PATENT OFFICE.

WALTER SNYDER, OF PHILADELPHIA, PENNSYLVANIA.

MANUFACTURE OF METAL FORMS.

1,352,845.

Specification of Letters Patent. Patented Sept. 14, 1920.

Application filed September 12, 1916. Serial No. 119,608.

To all whom it may concern:

Be it known that I, WALTER SNYDER, of Philadelphia, in the county of Philadelphia and State of Pennsylvania, have invented certain new and useful Improvements in the Manufacture of Metal Forms, whereof the following is a specification, reference being had to the accompanying drawings, in which the invention is represented as embodied in a form adapted for the drying of textile articles, such as stockings.

Forms of the general character above referred to have long been known and comprise a hollow metallic envelop having approximately the configuration of the article to be dried, and provided with means for supplying steam to the interior. In most cases, and particularly in that of a form intended for drying a stocking, it is desirable that the device should be relatively very flat, or thin, in comparison with its width in the direction which determines the external contour of the article to be dried.

Heretofore such forms have been either made of cast metal, usually brass or aluminum, or of sheet metal pieces riveted or brazed together. Cast metal forms have, of necessity, been more thick and bulging than is desirable, by reason of the practical difficulty attending the making of such casting. Furthermore, under the pressures to which these forms are subjected in use, cast metal forms have shown a tendency to leak. This is because castings develop air-holes caused by gases developed in the casting. These, together with sand holes on the surface, create channels by which the pressure escapes, the steam condensing on the outer surface of the form and injuring the article which is being dried. Sheet metal, by reason of the rolling process to which it has been subjected, is not subject to this objection, but forms of this character made of sheet metal have hitherto been non-integral, that is to say, the flat pieces of sheet metal have been secured together by riveting or soldering or brazing, leaving a joint where leakage is very liable to occur. When these forms are subjected to the relatively heavy internal steam pressure involved in their use, the metal distends and opens the seams of non-integral forms.

By my present invention I have devised a form, and a method of manufacturing the same, whereby the disadvantages of the thick

or bulging cast metal forms and the tendency of the form to leak under excessive pressure are entirely avoided, the form itself being relatively very flat and yet integral throughout.

In the accompanying drawings, I have illustrated the progressive steps which I employ in the method of manufacture, as well as the form itself in a finished condition.

Fig. I, is a perspective view showing the method of clamping and holding the assembled pieces of which the form is composed, during the peculiar novel welding operation employed, which enables me to attain the desired result.

Fig. II, is a side elevation of one of the metallic plates which constitute the form, showing also the steam pipe laid in position against the inner surface of the same.

Fig. III, is an edge view of the assembled parts before they are integrally united along the edges, showing both side pieces with the inserted tube.

Fig. IV, is an end view of the base of the form.

Figs. V, VI, and VII, are transverse sectional views, illustrating respectively the conditions at the commencement of assemblage, at the period preparatory to welding, and at the conclusion of the welding operation.

Fig. VIII, is an external side elevation of the finished form, indicating by dotted lines the position of certain internal parts.

Fig. IX, is a partial vertical section of an enlarged scale on the line IX, IX, of Fig. VIII.

Figs. X, XI, are details of some of the metallic pieces which I employ at the base region of the form, and

Fig. XII, is a detail view in perspective of a portion of the edge, illustrating the character of the welding operation which is peculiar to my method.

In carrying out my invention, I take, in the case of a stocking, two flat plates of sheet steel, having the desired contour, as indicated by 1, and 2, respectively. The metal should have substantial thickness, so as to permit the peculiar welding operation which will be described later on. Remote from the edges of the plates, on what may be called the median line of the figure, I place between the plates 1, and 2, a steam pipe 3, which extends down to near the

toe of the stocking form and is preferably provided with lateral outlets 4, and 5, adjacent to its inner extremity, so as to insure the free discharge of steam. The threaded rear, or base end of the pipe 3, is provided with a cylindrical coupling plug 6, whose details are shown in Fig. X, said plug having a threaded axial opening 7, and two projecting lugs 8, and 9, respectively. The 10 said projecting lugs enter between the plates 1, and 2, at the base of the form. A similar cylindrical plug 12, is arranged at the base of the form adjacent to the plug 6, the interspace between them being filled by a distance 15 piece 13, of thickness similar to that of the lugs 8, and 9. An approximately triangular distance piece 14, is arranged between the plates 1, and 2, at the base and outside of the plug 6, and another distance piece 15, is 20 arranged between the plates 1, and 2, at the opposite side of the base. The plates are preferably grooved on their internal faces as shown at 30, and 31, to provide channels for the flow of condensed steam to the outlet in the plug 12.

Assuming that the parts mentioned have been assembled substantially as shown in Figs. II, and III, the two plates 1, and 2, are then clamped together by any suitable 30 means, such as the clamp 17, and hand vice 18, see Fig. I, which hold the parts in assembled position, and the entire structure is held firmly in a vise 19, so as to be subjected to the welding treatment. At this 35 stage of the operation the plates 1, and 2, and pipe 3, may be considered as having the positions indicated in Figs. IV, and V. Thereafter the edges of the plates are forced 40 together so as to meet practically in the same plane, with a view to the subsequent welding operation, as well as to the desirable degree of flatness of the finished form, along one or both sides, the metal being bent convexly about the pipe 3 as a spacing 45 member and fulcrum so that the general cross section is that indicated in Fig. VI. For this purpose a hand vise, such as that indicated at 20, in Fig. I, may conveniently be used. The edge portions of the plates 50 1, and 2, are then welded together, so as to become integrally united, as indicated at 25, and 26, in Fig. VII, this being accomplished in the following manner:

The plates whose edges are to be united 55 by welding are clamped together in the angular relation indicated in Fig. VI, and held in a vise or other suitable clamping mechanism, the edges or margins of the plates being flush with one another. A 60 blast of intensely hot character and having suitable projective force, such as that of an oxy-acetylene blow pipe, is applied progressively along the laterally contacting edges in the direction of the arrow shown in Fig. 65 XII, the rate of forward movement being

relatively slow, so that the metal can become substantially melted, and the blast is projected from a point relatively close to the metallic edges, so that by the impact of the flame the metal is actually stirred. The blow pipe is manipulated by the operator, so as to give a slight circular movement or, more correctly speaking, spiral movement of the projected flame, as the latter is advanced along the edge, which results in a 7 complete merging of the metal from the respective edges followed by its sinking down somewhat into the angular interspace between the proximate faces of the plates, thus forming a weld which extends inwardly for a substantial distance, and avoiding any external overflow of the melted metal down the sides. Hence at the conclusion of the operation a substantially rounded edge is left without any projecting lateral boss or ridge. The application of the flame is carried toward one of the edge-clamping devices as near as is consistent with the avoidance of injury thereto, and thereafter the clamp is released and applied at a point a short distance farther on, toward which the welding is again progressively advanced until it has proceeded along the entire contour of the form including the base and tip. 95

Care should be taken to preserve the portion of the edge, which is for the time being undergoing the welding operation, in a substantially horizontal position, in order to avoid any tendency of the metal to run 100 along the edge, or away from the point of application.

This method of welding results in the union of the parts along their edges in an absolutely integral condition, without any 105 opening or joint.

When the process is completed the finished stocking form has the character indicated in Fig. VIII, the dotted line running along the external contour indicating in a 110 general way the depth of the weld, while the other dotted lines indicate the position of the pipe 3, extending along substantially the line of greatest thickness of the form in contact with the plates at its opposite sides 115 and its connected parts. The form is, it will be observed, of generally convex cross section,—i. e., it is thinnest at the edges and thickest at an intermediate point.

The above described welding operation 120 upon which the success of the process appears to depend, differs in its general character from any welding operation heretofore known to me, both in the method of its application, and in the resultant structure. Thus, the welding action is effected not merely by heat and pressure, but with the added feature of stirring and actually moving the metal by means of the projected blast, such stirring being conducted by an 125 130

organized manipulation of the blast so as to lay the merged, or united metal symmetrically along the edge, without external overflow and permit it to settle into the angular crevice between the adjacent faces of the plates, and thus extend the depth of the integral autogenous union. To distinguish the operation from the usual types of welding processes now practised, *i. e.*, lap-welding, butt-welding, or spot-welding, I term my method, "flush-edge angular-face welding," which expression points out the characteristics of difference.

Having thus described my invention, I claim:

1. The method of constructing a drying form which consists in superposing metal plates having the general contour of the article to be dried, with an intervening spacing member remote from their edges; bending the plates about said member as fulcrum so as to bring their edges together; and integrally uniting said edges to form a

relatively flat, hollow, unitary metallic envelop.

2. The method of constructing a drying form convex in cross section which consists in superposing metal plates having the general contour of the article to be dried, with an intervening spacing member extending along substantially the line of greatest thickness of the form; bending said plates about said member as fulcrum so as to bring their adjacent surfaces together at their corresponding edges; and integrally uniting said edges by flush-edge angular-face welding to form a relatively flat, hollow, metallic envelop.

In testimony whereof, I have hereunto signed my name at Philadelphia, Pennsylvania, this eleventh day of September, 1916.

WALTER SNYDER.
